UNITED STATES PATENT OFFICE

2,535,395

ELECTROPHORETIC APPARATUS FOR
RESEARCH

Alfred Dinsley, La Canada, Calif.

Application November 4, 1947, Serial No. 784,065

1 Claim. (Cl. 204—299)

1

My invention relates to apparatus for research, the primary object being to provide improved means by which solutions are separated into a number of constituents through the action of direct electrical current applied by positive and negative electrodes inserted therein by which resulting fractionated products can be obtained for examination, analysis or further use, by the chemist or pathologist in the advanced study of disease and for other purposes.

Among the objects of the invention is the production of simple and effective means by which a specimen in solution can be quickly and effectively reduced to its constituents by electrophoresis and removed for further examination and treatment, thus saving time and labor and enabling the user to more accurately, thoroughly and completely analyze and determine the composition and characteristics of fluids.

This application is a continuation, in part, of my companion application Serial Number 545,853, filed July 20, 1944, now abandoned.

In the accompanying drawing forming part of this specification, Fig. 1 is a diagrammatic elevation of an apparatus constructed in accordance with my invention, and Fig. 2 is a section of part of the apparatus taken on the line 2—2 of Fig. 1.

In the drawing, A indicates a U-tube having upwardly extending arms B and C hermetically sealed in a cooling jacket D. A drainage cock 10 is connected between the arms of said tube, and the lower portions on either side of the median portion of the U-tube are provided with draw-off cocks E and F which are extended through and outwardly from the cooling jacket. The cock E is connected with the negative arm B of the tube and the cock F is connected with the positive arm C. In this manner the fluid contents of either tube can be drawn off and removed after the solution in the tube has been subjected to the action of a charge of direct electrical current, as hereinafter described.

Intermediately in the structure of the tube and near the upper end portions of the arms of the U-tube, outlets for the vapor and/or gas products of reaction are indicated at 13 and 14, the outlet 13 being connected with arm B and the outlet 14 being connected with arm C, and both of said outlets being extended outwardly through the wall of the cooling jacket.

The structure above defined is preferably composed of transparent heat-resistant glass or suitable plastic material, whereby the action of the solution in the U-tube can be observed by the operator. In many different fields of chemistry or

2

medicine, it is desirable to observe the electrical characteristics of fluids, solutions, and the like, from the human body, or as solutions to be used for therapeutic purposes. These fluids or compositions in a majority of cases are capable of acting as electrical conductors. The method of my invention is based on the ability of solutions to conduct electrical current and on the fact that many materials are composed of ions carrying a characteristic electric charge, either negative or positive. A solution will, therefore, also carry a characteristic electrical charge per unit volume.

In order to investigate the properties of solutions, I have provided an apparatus by which the fluid which is placed in, and contained in the U-tube, is fractionated, by the passage of direct current of effective potential through the arms of the tube by the introduction of a bare positive electrode H in the fluid contained in the positive arm C of the U-tube, and, a bare negative electrode G in the fluid contained in the negative arm B of the U-tube. These electrodes are provided with plug terminals 15 and 16 which are removably and tightly secured in corresponding nipples 17 and 18. These nipples are extensions of the arms B and C through the wall of the cooling jacket D. Each electrode dips down deeply into the solution contained in the arms of the U-tube.

A positive and negative electrical current is applied to the terminals 15 and 16 and accompanying electrodes, by a suitable direct current circuit, such as 20, by which direct current of suitable voltage and amperage and containing milliammeter 21 and voltmeter 22, a regulating rheostat 23, and switch 24.

In carrying out the method of my invention a known quantity of solution to be tested and fractionated is introduced into the U-tube by removing one or both of the electrodes 15 or 16 and after the electrodes are adjusted the current is turned on by the switch 24 and regulated by the rheostat 23. Positively charged ions in the solution will then be attracted to the negatively charged electrode and negatively charged ions will be attracted to the positively charged electrode, the discharge of the charges carried by the ions into the conductors setting up electric currents which are characteristic of the solution which is being treated. The fluid or solution contained in the U-tube is thereby fractionated by the passage of current traversing between the positive and negative electrodes, one fractionated portion accumulating in the negative arm and

another type of fractionated portion accumulating in the positive arm of the U-tube. The separate fractionated portions can be respectively removed by opening the draw-off cocks E and F. These fractionations provide samples of components of the solution which can be examined, tested or treated.

During passage of electric current through the solution contained in the U-tube, the resistance of the liquid tends to generate considerable heat. The arms of the tube are, therefore, maintained at reduced temperature by the circulation of fluid coolant, such as water, through the jacket. This cold water may be supplied from any suitable source (not shown) which is adapted to be connected with the jacket D by the ingress and egress ducts 25 and 26.

Vapor and/or gas arising in the arms of the U-tube from the heated solution due to action of the electric current are conducted by the outlets 13 and 14 respectively to condensers I and J, by which further fractionations of the solution which is acted upon in the U-tube are condensed and made available for examination, testing and treatment. The condensed fractionated products emitted by the condensers are delivered into suitable containers 27 and 28. Following this treatment the U-tube can be drained by opening the drain cock 10, after which the drain cock is closed and the apparatus is ready to be recharged and the entire operation repeated.

My invention as above described provides an apparatus which permits the user to draw-off sharply divided and clearly separated opposing fractions which occur in the solutions which are treated in the U-tube. These fractions of a fluid may contain pathological end products, after the act of electrophoresis which may be negatively and/or positively charged, and can, therefore, be effectively separated to advantage for examination and testing.

I have found that changes in the solution in the human body, as, for instance, in the spinal-fluid, can be advantageously investigated by the use of my apparatus and by comparison of the readings obtained from a normal specimen in solution as compared with fluid from a pathological specimen. By observing the variation between the pathological specimen and the normal specimen solutions, an accurate check may be made as to the progress of a patient, and, the treatment administered may be modified accordingly.

It is believed that, the method of my invention and the apparatus provided for carrying it into

practice will enable much valuable data to be secured in investigating the properties of pathological fluids.

Modifications are contemplated in the apparatus shown and described within the spirit of the invention and within the scope of the following claim.

I claim:

Apparatus for subjecting pathological specimens in solution to electrophoresis, which consists of the following elements in combination: a U-tube having a pair of connected, vertically disposed arms for holding said solution, solution inlets entering the upper portions of each of said arms, a concentric cooling jacket hermetically sealed about said U-tube, cooling fluid inlet means near the bottom of said cooling jacket, cooling fluid outlet means near the top of said cooling jacket, a positive electrode exposed in the solution contained in one of said arms, a negative electrode exposed in the solution in the other of said arms, means for connecting the electrodes to a source of direct current so that the solution in said U-tube is subjected to electrophoresis and fractionation between said arms, valved outlet conduits near the lower portions of each arm and passing through said cooling jacket by means of which fractions of the solution in said arms are removed separately from the bottom of each of said arms, a common-drain, valved outlet conduit connected with the lower median line of the U-tube and passing through said cooling jacket for completely evacuating said tube, egress ducts near the upper portions of each of said arms extending from said tube outwardly through the walls of said cooling jacket for egress of gases produced during electrophoresis, and condensers connected with each of said egress ducts effective to remove from each arm and to condense and collect separately therefrom further fractions in liquid form.
